UNITED STATES PATENT OFFICE.

FREDERICK A. BEAUCHAMP, OF BERKELEY, CALIFORNIA.

PROCESS AND APPARATUS FOR RECOVERY OF PRECIOUS METALS.

Application filed August 4, 1920. Serial No. 401,166.

To all whom it may concern:

Be it known that I, FREDERICK A. BEAUCHAMP, a British subject, residing at Berkeley, in the county of Alameda and State of California, have invented a new and useful Improvement in Process and Apparatus for Recovery of Precious Metals, of which the following is a specification.

This invention relates to the recovery of precious metals by amalgamation with mercury.

The invention includes a novel process and apparatus for maintaining a surface of fluid mercury at an angle from the horizontal desired and moving the pulp containing the mineral particles over the surface of the mercury by the hydrostatic head given to the pulp entering the machine.

One form of apparatus for practicing the invention is illustrated by way of example in the accompanying drawing, in which the figure is a vertical central sectional view of an apparatus especially designed for the recovery of precious metals from their ores; particularly metals such as platinum, osmium and what is known as rusty or coated gold, all of which are not amalgamable by simple contact with a pure mercury surface.

Although there are on record a few instances where the ore has been milled in a solution of cyanide and then successfully treated by the amalgamation process consisting of passing the pulp of ground ore and cyanide solution over amalgamated copper plates in the usual way, yet in most instances it has been found that unless very dilute cyanide solutions are used in the process the amalgam on the plates is attacked by the cyanide solution, the gold being apparently dissolved and the mercury running off, leaving the plates bare, and thus rendering further amalgamation impossible. Even where a satisfactory amalgamation has been recorded as having been made in this way yet the copper plates have been found to be attacked through the coating of amalgam, necessitating their frequent renewal.

Now it is in the case of most ores a desirable procedure to mill in a cyanide solution and in the case of many ores, especially those containing coarse free gold and metallic silver, it would be beneficial to remove such coarse and free metal by amalgamation prior to the usual methods of cyanide treatment, and it is to render such a combination feasible and possible whenever so desired

that I have developed the machine herein-after to be described.

By my invention I produce a surface of fluid mercury that is maintained at any angle from the horizontal that may be desired by adjusting the speed of rotation, and the pulp of ground ore and solution is kept moving over its surface by the hydrostatic head given to the pulp entering the machine; the particles of precious metal being heavier than the gangue are projected by the centrifugal force towards the surface of the mercury wherewith they amalgamate as soon as contact with the surface is established.

With particular reference to the accompanying drawing, the machine there shown is especially designed to overcome various objections in the application of the principle of amalgamation by sodium amalgam in the treatment of platinum, rusty gold, etc. The machine comprises a bowl 10 having a smooth inner surface. This bowl is carried by a vertical shaft 11 which is supported by bearings 12. The shaft and bowl are rotated by means of bevel gears 13 which are driven by a horizontal shaft 14. The bowl is formed with an inwardly projecting lip 15 at its upper end and a curved rim or lip 16 terminating above a discharge launder 17.

A cylindrical feed spout 18 is supported on a frame 19 and extends into the bowl to a point short of the bottom thereof where it is preferably provided with a constricted neck 18^b. A dynamo or generator 27 is operated by the driving shaft 14. This generator is electrically connected to the cylinder 18 by a connection 28 and with the bowl 10 by a connection 29. The cylinder 18 constitutes the anode and the bowl the cathode. A mercury layer or film 20 is built up along the walls of the bowl to seal the bottom of the feed spout.

In the operation of the device, sufficient mercury is introduced into the bowl to create a film as shown at 20 and pulp is fed into the cylinder 18. Since the cylinder extends downwardly into the film of mercury and has its exit closed thereby, the effect is to force the pulp through the mercury by means of hydrostatic head built up in the cylinder 18. This brings the particles of the precious metal into more intimate contact with the mercury than would otherwise occur. The pulp having passed over the mercury sur-

face and deposited its coarse particles of precious metal therein, is discharged over the top of the bowl and enters the discharge launder 17 from which any particles of precious metal that may have escaped amalgamation can be recovered.

The most important result effected by the machine above described is the provision of a fluid bed or film of mercury that is independent of the support of a plate of metal capable of being amalgamated or wetted by it, as in the case of the ordinary amalgamated copper plate. The advantage of this is that the gold and silver amalgam formed remains fluid instead of becoming pasty or even hard as on a copper plate, and therefore the gold and silver contained therein are hardly appreciably affected by the dissolving action of the cyanide solution; neither has the mercury any supporting metal that can be attacked by the said solution. The difficulty of applying such a principle without the use of a machine of the type specified in my invention lies in the fact that mercury in the fluid state naturally assumes the horizontal position, and an inclined plane surface cannot be produced, and if ore pulp were passed over such a horizontal bath of fluid mercury at the proper speed for amalgamation, the coarser particles would settle thereon and silt up the surface rendering further amalgamation impossible.

It has long been known that metals such as platinum, osmiridium and rusty gold through not amalgamable by contact with mercury alone are easily wetted and held by mercury in which metallic sodium has been dissolved, or in other words by sodium amalgam. It usually happens in such cases, however, that as soon as the sodium has been abstracted from the mercury by combination with the water in the ore-pulp, according to the reaction $\text{Na} + \text{H}_2\text{O} = \text{NaOH} + \text{H}_2$ the mercury ceases to hold the particles of precious metals, which as soon as the film of mercury recedes from them are free to be carried away with the gangue by the flow of pulp. It is thus important that if the precious metal particles are to be kept wet by the mercury and thereby kept entangled by it and retained while the gangue flows away, a continual supply of metallic sodium must be maintained in the bath of mercury. This can best be accomplished by dissolving a sodium salt such as sodium chloride or sodium hydroxide in the water used to suspend the crushed ore, and by means of an electric current electrolyzing the sodium salt, continually depositing metallic sodium on the mercury which is made the cathode of the system.

The difficulty heretofore experienced in applying this principle in practice has lain in the fact that if an inclined amalgamated copper plate be used and the pulp allowed

to flow over it, the thickness of the film of electrolyte is not sufficient to make it possible to have an anode in contact with the electrolyte without its forming an electrical contact with the cathode (in this case the amalgamated copper plate) and thereby short circuiting the current and making electrolysis impossible. There have been various schemes suggested to obviate this difficulty. One such scheme is to have an incline plane of wood or other suitable material wherein transverse grooves or riffles are constructed and filled with mercury; the pulp, as it passes over these riffles is intended to be raised to such a thickness as to admit of the placing of an anode in contact with it and yet sufficiently far from the mercury surface or cathode as to allow of the electrolysis of the electrolyte without danger of contact with the cathode and consequent short-circuiting of the current. This scheme, however, has not proven successful in practice.

In order to obviate the above difficulties, there has been suggested a machine consisting of a slowing revolving horizontal cylinder lined with an amalgamable metal, e. g. copper, at a suitable distance from which, all around the periphery, are placed horizontal bars of some conducting substance (such as iron or carbon) to act as anodes. The ground ore in a medium of solution of sodium salt is run through the cylinder, the solution being simultaneously electrolyzed by the current and sodium deposited on the amalgamated copper surface, thereby causing the particles of precious metal to adhere thereto and thus become separated from the gangue. The difficulty with this apparatus has been found to be that owing to the depth of the bed of pulp passing through the machine, coupled with the agitation action produced by the revolution of the cylinder, only the larger and heavier particles of precious metal can come in contact with the mercury surface and become entangled thereon, the lighter particles remaining in suspension in the electrolyte and being carried out with the tailing.

It will be seen from the foregoing that I produce an inclined surface of mercury at any angle from the horizontal that may be desired, by adjusting the speed of rotation of the machine. The pulp in a medium of water containing a salt of sodium in solution passes between the mercury surface and the anode, during which period by the action of the current, sodium is deposited from the electrolyte on the mercury surface forming sodium amalgam, while simultaneously the precious metal particles are, by the action of centrifugal force, carried towards the surface of the sodium amalgam where they are at once caught and held as soon as contact is established.

The hydrostatic head under which the pulp enters the machine keeps the gangue particles in the pulp continually moving over the mercury surface and discharging over the top, thus preventing any silting up of the amalgamated surface, and leaving it free to continue its functions. The drawing shows an apparent contact between the bottom edge of the anode and the mercury cathode but this contact is made by an extension of non-conducting material 30 such as hard rubber or bakelite, so as to avoid electrical contact between the two electrodes. This shape of the neck, although not an essential part of the invention, has been found to enhance the effect in certain cases, since it thus ensures a more intimate contact between the ore particles and the sodium amalgam.

Having thus described my invention, what I claim and desire to secure by Letters Patent is—

1. A machine for the recovery of precious metals by amalgamation with mercury, comprising a centrifugal bowl so shaped as to confine a layer of fluid mercury around its

walls at an angle to the horizontal, a feed spout for the pulp extending downwardly into the bowl and sealed at its lower end by the mercury, the lower portion of said feed spout being formed of insulating material.

2. A machine for the recovery of precious metal by amalgamation with mercury, comprising a rotatable bowl shaped to confine a layer of fluid mercury around its walls by centrifugal action when rotating, a feed spout extending downwardly into the bowl, the lower end of said spout being formed of insulating material and adapted to be sealed by the mercury, an electrical connection for the feed spout constituting the anode, and an electrical connection for the bowl constituting the cathode for directing electrical current through the pulp.

In testimony whereof I have hereunto set my hand in the presence of two subscribing witnesses.

FREDERICK A. BEAUCHAMP.
